United States Patent Office

Des. 211,133

Patented May 21, 1968

211,133

GUITAR BODY OR SIMILAR ARTICLE

Louis S. Holly, Highland Park, N.J., assignor, by mesne assignments, to The Danelectro Corporation, Neptune City, N.J., a corporation of New York

Filed June 27, 1967, Ser. No. 7,618

Term of patent 14 years

(Cl. D56—1)

FIG. 5

FIG. 6

FIG. 7

FIGURE 1 is a front elevational view of a guitar body or similar article showing my new design;

FIGURE 2 is a side elevational view thereof;

FIGURE 3 is a rear elevational view thereof;

FIGURE 4 is a side elevational view of the other side thereof;

FIGURE 5 is a top end view thereof;

FIGURE 6 is a bottom end view of the other end thereof; and

FIGURE 7 is a front perspective view thereof.

The broken line showing is of the neck and head of the guitar body and is for illustrative purposes only.

I claim:

The ornamental design for a guitar body or similar article, as shown and described.
